UNITED STATES PATENT OFFICE

162,348

CONTAINER FOR SLIPS OR THE LIKE

Robert B. Senderowitz, Allentown, Pa.

Application July 17, 1950, Serial No. 11,232

Term of patent 14 years

(Cl. D58—2)

To all whom it may concern:

Be it known that I, Robert B. Senderowitz, a citizen of the United States of America, residing in Allentown, county of Lehigh, and State of Pennsylvania, have invented a new, original, and ornamental Design for a Container for Slips or the like, of which the following is a specification, reference being had to the accompanying drawing, forming part thereof, wherein:

Figure 1 is a front perspective view of a container for slips or the like, showing my new design in closed position.

The rear of the container for slips or the like, shown in Figure 1, is substantially plain in appearance.

I claim:

The ornamental design for a container for slips or the like, substantially as shown and described.

ROBERT B. SENDEROWITZ.
